LET-OFF MECHANISM FOR LOOMS

William P. Bodie, Newberry, S. C.

Application May 7, 1938, Serial No. 206,659

5 Claims. (Cl. 139—107)

This invention relates to a let-off mechanism for looms, and it is primarily an object of the invention to provide means by which effective strain or tension may be imposed automatically upon the yarn beam.

It is also an object of the invention to provide a tensioning structure for the beam including a rotatable element in driven connection with the beam and which carries a plurality of radially movable weighted members together with a brake shoe for coaction with said weighted members, said brake shoe being so mounted as to automatically move away from the axis of rotation of the rotatable element as the diameter of the thread upon the beam diminishes.

The invention consists in the details of construction and in the combination and arrangement of the several parts of my improved let-off mechanism for looms whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a fragmentary view in top plan illustrating a let-off mechanism constructed in accordance with an embodiment of my invention and in applied position;

Figure 2 is a vertical sectional view taken substantially on the line 2—2 of Figure 1 looking in the direction of the arrow;

Figure 3 is a sectional view taken substantially on the line 3—3 of Figure 1 looking in the direction of the arrow;

Figure 4 is a fragmentary sectional view taken substantially on the line 4—4 of Figure 2;

Figure 5 is a fragmentary view in outer end elevation of the structure illustrated in Figure 4 with the retaining bands omitted.

As the present invention relates solely to the let-off mechanism in the accompanying drawings I have only illustrated so much of a loom frame as is necessary to properly set forth the features of the let-off mechanism.

As disclosed in the accompanying drawings, F denotes the frame of a loom which may be of any desired construction and which carries in any desired manner a yarn beam or warp beam B. Each end portion of the beam B carries a gear 1 of desired radius which is adapted to be selec-

tively engaged with a pinion 2 carried by a shaft 3 rotatably supported by the frame F and extending laterally beyond a side thereof. Fixed, as at 4, for rotation with the shaft 3 are the disks 5 spaced apart as desired lengthwise of said shaft 3.

These disks 5 are of desired radius and are provided in their opposed faces with the circumferentially spaced and radially disposed grooves or channels 6 which open through the peripheral edges of the disks 5 as is clearly illustrated in the accompanying drawings. Each of the grooves or channels 6 of a disk 5 is parallel to a groove or channel 6 in the opposed face of the second disks 5 or, in other words, the grooves or channels 6 of the disks 5 are arranged in pairs with the grooves or channels 6 of each pair in proper relation so that there may be slidably engaged therein the guide flanges 7 extending outwardly from the weighted members 9. Each of the members 9 at the longitudinal center of its outer marginal portion is provided with a relatively large recess 10, the inner or bottom wall 11 of which is outwardly rounded in order for the most effective coaction with the arcuate brake shoe 8 which is received within the recess 11 of each of the members 9 as the disks 5 rotate.

After the weighted members 9 have been properly applied between the disks 5, the extent of their outward radial movement is limited by contact with the holding bands 12 which are detachably secured by the screws 14 or otherwise as may be preferred to the peripheral edge faces of the disks 5. These bands 12, as is particularly illustrated in Figure 4, are of a width sufficient to close the outer ends of the grooves or channels 6 so that the contact of the flanges 7 of each of the members 9 therewith is assured.

The brake shoe 8 is elongated and disposed on desired radius so that it can be maintained in proper effective position for coaction with the weighted members 9. This brake shoe 8 is vertically disposed and the lower end portion thereof is pivotally supported, as at 15, within a slot 16 disposed lengthwise through an elongated beam 17. This beam 17 has its inner end portion fixed, as at 18, to a rock shaft 19. This shaft 19 is rotatably supported by the frame F at a desired point in advance of the shaft 3 and is disposed transversely of the frame F. The shaft 19 also extends a desired distance inwardly of the frame F and said inner portion of the shaft 19 has fixed thereto, as at 20, for rocking movement therewith an arm 21 disposed toward the beam B. The outer or free end portion of this arm 21 carries a shoe 22 for contact from

above with the thread or yarn wound upon the beam B. This shoe 22 through the action of the shoe 8 is automatically maintained in proper contact with the thread or yarn on the beam B to 5 assure the requisite tension being maintained on said yarn or thread at all times during a weaving operation. The mounting 20 of the arm 21 upon the shaft 19 is such as to readily allow an adjustment of the arm 21 around the shaft 19 as the 10 requirements of practice may deem advisable and necessary.

The pivoted or connected end portion of the arm 17 is continued by an elongated tail arm 23 which has adjustably mounted thereon a balancing weight or poise 24 which is maintained in desired selective adjustment through the instrumentality of the clamping screw 25 or the like.

Pivottally connected, as at 26, to the central portion of the shoe 8 is the outer end portion 20 of an elongated rod 27. This rod 27 is of a length to freely extend through the opening 28 provided in the outer portion of the arm 17. Slidably mounted upon this rod 27 are the blocks 29 held to the rod 27 by the locking screws 30 25 or the like. These blocks 29 are formed to provide the opposed coacting cam surfaces 31 so that upon rotation of one of these blocks 29 around the rod 27 with respect to the other, adjustment may be had of the tension of the coil 30 spring 34 encircling the rod 27 interposed between the arm 17 and the lowermost block 29. To rotatably adjust either of these blocks 29 it is only necessary to release a clamping or holding screw 30 and, of course, after the desired 35 adjustment has been effected such screw may again be tightened.

The spring 34 provides means for constantly urging the shoe 8 toward the shaft 3 and within the recesses 10 of the weighted members 9 as 40 such weighted members swing or move upwardly as the disks 5 rotate. As these weights or members 9 pass upwardly beyond the vertical center they will swing outwardly toward the peripheries of the disks 5 and thus provide sufficient retardation to the rotation of the beam B to assure 45 effective tension or resistance being maintained upon the thread or yarn as drawn from said beam.

The fuller the winding of the thread or yarn 50 upon the beam B the greater resistance must be imposed upon the thread or yarn by the shoe 22 under the action of the ascending weighted members 9 and, therefore, upon the initial placement of a fully wound beam, the arm 21 will 55 raise the arm 17 to bring the shoe 8 into a position to coact with the ascending weighted members 9 to move the same to their innermost positions so that maximum tension will be imposed upon the beam. However, as the diameter of 60 the thread diminishes the arm 17 will correspondingly swing downwardly and the shoe 8 outwardly from the shaft 3, thus permitting the rising weighted members 9 to assume positions further away from the shaft 3 to reduce the 65 tensioning action of the descending weighted members 9.

The extent of downward swinging movement 70 of the arm 17 is limited by contact of said arm with the outstanding stop member 32 adjustably held, as at 33, to the frame F.

From the foregoing description it is thought 75 to be obvious that a let-off mechanism for looms constructed in accordance with my invention is particularly well adapted for use by reason of the convenience and facility with which it may

be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. A let-off mechanism for looms comprising a rotatable member having driven connection with the rotating beam of a loom, weighted members carried by said rotatable member and having sliding movement radially of the rotatable member, said weighted members moving outwardly of the rotatable member as said weighted members move downwardly, and means under control of the thread on the beam for holding the weighted members inwardly of the rotatable member as said weighted members move downwardly.

2. A let-off mechanism for looms comprising a rotatable member for driven connection with the beam of a loom, a rock arm positioned adjacent to the rotatable member, an upstanding shoe carried by said rock arm, means associated with said rock arm and coacting with the thread on the beam to allow said rock arm to swing away from the axial center of the rotatable member as the diameter of the thread on the beam diminishes, weighted members carried by the rotatable member and free for sliding movement in a direction radially of the rotatable member, said weighted members as they assume positions away from the center of the rotatable member imposing tension on the thread as pulled from the beam, said weighted members moving in such direction as they travel downwardly, and a shoe carried by the rock arm for coaction with the weighted members to hold said weighted members inwardly of the rotatable member as said weighted members move downwardly.

3. A let-off mechanism for looms comprising a rotatable member for driven connection with the beam of a loom, a rock arm positioned adjacent to the rotatable member, an upstanding shoe carried by said rock arm, means associated with said rock arm and coacting with the thread on the beam to allow said rock arm to swing away from the axial center of the rotatable member as the diameter of the thread on the beam diminishes, weighted members carried by the rotatable member and free for sliding movement in a direction radially of the rotatable member, said weighted members as they assume positions away from the center of the rotatable member imposing tension on the thread as pulled from the beam, said weighted members moving in such direction as they travel downwardly, a shoe carried by the rock arm for coaction with the weighted members to hold said weighted members inwardly of the rotatable member as said weighted members move downwardly, said second shoe being in pivotal connection with the rock arm, and yielding means for resisting the movement of the shoe in a direction away from the axial center of the rotatable member.

4. A let-off mechanism for looms comprising a rotatable member for driven connection with the beam of a loom, a rock arm positioned adjacent to the rotatable member, an upstanding shoe carried by said rock arm, means associated with said rock arm and coacting with the thread on the beam to allow said rock arm to swing

- away from the axial center of the rotatable member as the diameter of the thread on the beam diminishes, weighted members carried by the rotatable member and free for sliding movement 5
5 in a direction radially of the rotatable member, said weighted members as they assume positions away from the center of the rotatable member imposing tension on the thread as pulled from the beam, said weighted members moving in such 10
10 direction as they travel downwardly, a shoe carried by the rock arm for coaction with the weighted members to hold said weighted members inwardly of the rotatable member as said weighted members move downwardly, and a shoe 15
15 counter-balance operatively carried by the rock arm.
5. A let-off mechanism for looms comprising a rotatable member for driven connection with the beam of a loom, a rock arm positioned adjacent to the rotatable member, an upstanding shoe carried by said rock arm, means associated
- with said rock arm and coacting with the thread on the beam to allow said rock arm to swing away from the axial center of the rotatable member as the diameter of the thread on the beam diminishes, weighted members carried by 5
the rotatable member and free for sliding movement in a direction radially of the rotatable member, said weighted members as they assume positions away from the center of the rotatable member imposing tension on the thread as pulled from the beam, said weighted members moving in such direction as they travel downwardly, and a shoe carried by the rock arm for coaction with the weighted members to hold said weighted members inwardly of the rotatable member as 10
10 said weighted members move downwardly, said weighted members having recesses in which are received the shoe as the weighted members move upwardly.
